UNITED STATES PATENT OFFICE.

JOHN P. FOGARTY, OF WESTFIELD, MASSACHUSETTS, ASSIGNOR TO WESTFIELD MANUFACTURING COMPANY, OF WESTFIELD, MASSACHUSETTS, A CORPORATION OF MASSACHUSETTS.

DESIGN FOR A HANDLEBAR GRIP.

Application filed October 24, 1921. Serial No. 510,149. Term of patent 7 years.

To all whom it may concern:

Be it known that I, JOHN P. FOGARTY, a citizen of the United States, residing at Westfield, in the county of Hampden and State of Massachusetts, have invented a new, original, and ornamental Design for a Handlebar Grip, of which the following is a specification, reference being had to the accompanying drawing, forming a part thereof.

In the drawing—

Fig. 1 is a side elevational view of a handlebar grip including my new design.

Fig. 2 is a cross sectional view on the line 2—2 of Fig. 1.

I claim:

The ornamental design for a handlebar grip as shown.

JOHN P. FOGARTY.
